UNITED STATES PATENT OFFICE

107,577

DESIGN FOR A PARKING METER HOUSING

John B. McGay and George E. Nicholson, Tulsa,
Okla., assignors to Dual Parking Meter Com-
pany, Oklahoma City, Okla., a corporation of
Delaware

Application December 14, 1936, Serial No. 66,522

Term of patent 7 years

To whom it may concern:

Be it known that we, John B. McGay and George E. Nicholson, citizens of the United States, residing at Tulsa, in the county of Tulsa and State of Oklahoma, have invented a new, original, and ornamental Design for a Parking Meter Housing, of which the following is a specification, reference being had to the accompanying drawing, forming a part thereof.

Figure 1 is a perspective view showing the front and one side of the housing; and,

Figure 2 is a view similar to Figure 1, but shows the rear and the other side of the housing.

We claim:

The ornamental design for a parking meter housing, as shown.

JOHN B. McGAY.
GEORGE E. NICHOLSON.
